(57) **CLAIM**

The ornamental design for a freezer stick, as shown and
described.

DESCRIPTION

FIG. 1 is a top, front, and right side perspective view of a first
embodiment of a freezer stick showing my new design;

FIG. 2 is a front plan view thereof;

FIG. 3 is a right side view thereof;

FIG. 4 is a rear plan view thereof;

FIG. 5 is a left side view thereof;

FIG. 6 is a top plan view thereof;

FIG. 7 is a bottom plan view thereof;

FIG. 8 is a top, front, and right side perspective view of a
second embodiment of a freezer stick showing my new
design;

FIG. 9 is a front plan view thereof;

FIG. 10 is a right side view thereof;

FIG. 11 is a rear plan view thereof;

FIG. 12 is a left side view thereof;

FIG. 13 is a top plan view thereof; and,

FIG. 14 is a bottom plan thereof.
